UNITED STATES PATENT OFFICE.

GEORGE P. CRAGIN, OF FERGUS FALLS, MINNESOTA. ASSIGNOR, BY DIRECT AND MESNE ASSIGNMENTS, TO C. D. BAKER AND IDA L. CRAGIN, BOTH OF SAME PLACE.

NUT-LOCK.

SPECIFICATION forming part of Letters Patent No. 340,661, dated April 27, 1886.

Application filed December 29, 1885. Serial No. 187,009. (No model.)

To all whom it may concern:

Be it known that I, GEORGE P. CRAGIN, a citizen of the United States, residing at Fergus Falls, in the county of Otter Tail, State of Minnesota, have invented certain new and useful Improvements in Nut-Locking Bars, of which the following is a specification, reference being had therein to the accompanying drawings.

10 My invention relates to a nut-locking bar; and it consists in the construction and arrangement of the same, which will be more fully hereinafter described, and definitely pointed out in the claim.

15 The object of my invention is to provide a nut-locking bar for securing a nut in such a position that it cannot turn or become displaced from its bolt, said bar being simple in its construction, strong and durable, and easily 20 secured in its desired position. I attain these objects by the device illustrated in the accompanying drawings, wherein like letters of reference indicate similar parts in the several views, and in which—

25 Figure 1 is a perspective view of a portion of a rail illustrating the joint thereof with the angle-plate secured in position and with my improved nut-locking bar applied under the nuts. Fig. 2 is a perspective view of my improved nut-locking bar detached. Fig. 3 is a view similar to Fig. 1, but with the locking-bar applied in connection with an ordinary fish-plate.

30 A indicates a portion of a rail showing a joint with the angle-plate B set in position over the joint.

C represents the nuts of the securing-bolts, which pass through the rail A, angle-bar B, and under which my improved locking-bar D is placed, said locking-bar being secured to the sleepers E by suitable means. The locking-bar D is formed of metal, and has two end seats, d, which rest on the angle-plate B, and conform to the contour thereof. The said 45 seats d are provided with apertures d' in their lowermost part, through which spikes may be driven into the sleepers E. The end seats, d, are connected by metal web d², cast integral therewith, said web being of less transverse

breadth and vertical thickness than the end 50 seats, and in consequence of such formation leaves a recess between the said seats, allowing them to extend outwardly beyond the web d². The under side of this web d² does not rest upon the angle-plate B, but has cast therewith 55 a series of projections, d³, which form seats for this portion of the locking-bar, which rest on the angle-plate. Between each of these projections d³ an arch, d⁴, is formed, by which means greater strength with a less amount of 60 metal is obtained.

In Fig. 3 I have illustrated the locking-bar D, applied in connection with an ordinary fish-plate. In this instance the rest d is situated in the central portion of the bar, the web d² 65 extending at about right angles from either side thereof. The projections d³ are constructed on each end of this bar, and two arches, d⁴, one on each side of the central seat, d, are shown. Only one spike is required to 70 secure this form of locking-bar D, which is driven through the recess d', formed in the central seat, d.

To apply my improved nut-locking bar the operation is as follows: The angle-plate B or fish-plate having been secured over the joint in the rail A, and the nuts C, with their lower faces on a true line, screwed home, the locking-bar D is placed under the lower faces of the nuts C, and secured to the sleepers E by spikes 80 driven through the recesses d', formed in the seats d. When the locking-bar is in its position, the end or central seats will rest firmly on the angle-plate or rail and against the vertical portion of the angle-plate or fish-plate. 85 This locking-bar is light and simple in its construction, dispensing with the use of a large quantity of metal, and thus avoiding the casting of a cumbersome and heavy bar. By the formation of arches between the projections 90 formed integral with the central web the bar is strengthened and rendered durable. A further advantage of this bar is that it conforms to the contour and arrangement of any angle-plate or fish-plate, thus avoiding the necessity 95 of constructing it to fit the plate to which it is desired to apply it.

It is obvious that any form of nut can be

readily used in connection with this bar other than those shown and described without changing the form of the bar and necessitating a departure from the nature and principle 5 of my invention.

I am aware that lock bars have been used in connection with angle and fish plates, which are constructed to conform to the shape of the plate used, and such I do not broadly claim; 10 but

What I do claim as new, and desire to secure by Letters Patent, is—

As an article of manufacture, a nut-locking bar consisting of two end seats having securing-

recesses formed therein, a central web cast integral with the end seats of less transverse breadth and vertical thickness than said seats, and projections forming seats for said web, having arches formed between them, whereby the bar is rendered light in construction, 15 strong, and durable, substantially as described.

In testimony whereof I affix my signature in presence of two witnesses.

GEORGE P. CRAGIN.
